UNITED STATES PATENT OFFICE.

JAMES MILLER, OF SOUTH GLENS FALLS, NEW YORK.

CLOTHESLINE.

1,411,927.

Specification of Letters Patent.

Patented Apr. 4, 1922.

Application filed August 8, 1921. Serial No. 490,656.

To all whom it may concern:

Be it known that I, JAMES MILLER, a citizen of the United States, residing at South Glens Falls, in the county of Saratoga and State of New York, have invented new and useful Improvements in Clotheslines, of which the following is a specification.

My present invention has reference to an endless clothes line and supporting means therefor.

The primary object of my invention is to produce a means whereby an endless clothes line will be effectively supported to not only economize the space required for the clothes thereon but to provide means whereby a pull on the line from any portion thereof will draw the entire line and the clothes thereon toward the operator so that the clothes may be arranged on the line and removed therefrom without necessitating the operator traveling all around the line.

A further object is to produce a clothes supporting means in which the clothes will be fully exposed to the sun and air, and which, while of an extremely simple construction, shall be strong and efficient so as to support thereon a comparatively great number of garments to be dried.

The foregoing, and other objects which will appear as the nature of the invention is better understood, may be accomplished by a construction, combination and operative association of parts, such as is disclosed by the drawings which accompany and which form part of this specification.

In the drawings:—

Figure 1 is a perspective view of the improvement.

Figure 2 is a horizontal sectional view approximately on the line 2—2 of Figure 1.

Figure 3 is a sectional view on the line 3—3 of Figure 1, on an enlarged scale.

Figure 4 is a perspective view of one of the substantially bell-shaped guide rollers.

Figure 5 is a view illustrating a different manner in which the device may be supported.

Figure 6 is a sectional view on the line 6—6 of Figure 5.

Figure 7 is a plan view of a modification, the supporting means therefor being in section.

As disclosed in Figure 1 of the drawings, I may plant in a lawn any desired number

of spaced uprights or posts 1. These posts 55 may be arranged in any desired position or relation with respect to each other.

The improvement contemplates the employment of bracket members, one of said bracket members being secured to each of 60 the posts 1. Each bracket comprises a plate 2 that is secured in any desired manner to a post. From the plate 2, adjacent to the upper end thereof there is extended a right angularly disposed arm 3, the said arm being 65 braced to the top of the plate, as at 4. To the outer end of the arm 3 there is either integrally formed or secured a bar or arm 5, and to the inner face of this bar 5 adjacent to the lower end thereof there is secured an 70 inwardly extending arm 6 that is parallel with the arm 5. It will thus be noted that the outer end of the bracket is substantially U or yoke shaped, and preferably the arm 6 is braced to the bar 5 as indicated by the 75 numeral 7. The arms of the yoke portion of the bracket are grooved longitudinally upon their confronting faces, as at 8 respectively, and in these grooves there are springs 9 respectively. Preferably the grooves are 80 substantially in the nature of key-hole slots, the inner ends of the same being enlarged and preferably rounded, and in these rounded portions indicated for distinction by the numeral 10, the springs 9 are seated. 85 The springs 9 are retained in the enlarged portions 10 of the grooves, at the ends thereof opposite the bar 5, by pins 11 which pass transversely through the arms 3 and 6, and, of course, through the grooves in the said 90 arms. The opposite or outer ends of the springs are free, but are held against movement entirely through the grooves through the medium of stop elements. The stop elements are preferably in the nature of bolts 12 that 95 pass transversely through the grooved ends of the arms, the said bolts being engaged by nuts 13 which permit of the removal of the bolts, when desired. The bolts are removed when the springs are to be arranged in the 100 grooves, and likewise are removed when a weakened spring is to be removed and replaced by a new spring. The grooves receive therein trunnions 14 formed on the opposite ends of solid but substantially bell-shaped rollers 15. The free ends of the 105 springs contact with the trunnions, and consequently force the rollers 15 toward the

outer ends of the arms 3 and 6. The rollers have arranged therearound an endless line 16 upon which the clothes are to be supported.

- 5 It will be apparent, from the foregoing description when taken in connection with the drawings that the clothes line 16 will be held from downward movement by its contact with the skirt portion 17 of the rollers
10 15, and being influenced by the spring will be sustained upon the rollers regardless of the weight of the clothes thereon. It will also be apparent that the contact members or bolts 12 limit the outward movement of
15 the rollers through the yoked ends of the bracket and it will be also apparent that the laundress may stand at any desired spot with respect to the clothes line to arrange thereon the clothes to be dried or to remove such
20 clothes therefrom, a pull on the line bringing all of the clothes toward or away from the operator. It will be further apparent that the line may be arranged where a portion is sheltered, as for instance, one of the
25 brackets may be secured to the post of a porch, so that the operator need not expose herself to inclement weather in removing the clothes or arranging the same on the line.
- In Figures 5 and 6, the construction is substantially similar to that previously described, but the bracket, indicated for distinction by the numeral 18, has its inner member or plate 19, adjacent to its top provided with a round opening and on a support 20 there
35 is secured a tubular member, such as a pipe 21, the said pipe passing through the opening, a binding element 22 being provided

upon the arm and entering the opening to contact with the pipe 21.

In Figure 7, the inner plate, similar to 40 the plate 2 may be in the nature of an angle member 23, and one of the flanges 24 of the said plate is provided with openings 25, and through these openings pass the securing means that sustain the plates on a support. 45

Having described the invention, I claim:—

1. In a support for an endless clothes line, brackets having yoke portions, rollers having trunnions journaled in the yoke portions of the brackets, spring means contact- 50 ing the trunnions and influencing the rollers outward of the yokes, means limiting the movement of the rollers in such direction, and said rollers having trained therearound an endless clothes line. 55

2. In a support for an endless clothes line, brackets including plates designed to be secured to supports and having yoke members on one of the faces thereof, said yokes having their outer ends open and having their 60 confronting faces grooved longitudinally, a spring in each of said grooves, a roller having trunnions designed to be received in the grooves and to be contacted by the springs, removable means limiting the outward move- 65 ment of the rollers, each of said rollers comprising a solid substantially bell-shaped member whose skirt portion is arranged at the bottom end thereof, and said rollers having trained therearound an endless clothes 70 line.

In testimony whereof I affix my signature.

JAMES MILLER.
